UNITED STATES PATENT OFFICE.

HARVEY C. STROUT, OF GLOUCESTER, MASSACHUSETTS, ASSIGNOR TO TRAFFIC SIGN & SIGNAL COMPANY, OF GLOUCESTER, MASSACHUSETTS, A CORPORATION OF MASSACHUSETTS.

TRAFFIC-SIGN.

1,254,862.

Specification of Letters Patent. Patented Jan. 29, 1918.

Application filed March 3, 1917. Serial No. 152,217.

To all whom it may concern:

Be it known that I, HARVEY C. STROUT, a citizen of the United States, residing at Gloucester, county of Essex, State of Massachusetts, have invented an Improvement in Traffic-Signs, of which the following description, in connection with the accompanying drawing, is a specification, like characters on the drawing representing like parts.

10 This invention relates to traffic signs such as are used in streets for directing traffic. The object of the invention is to provide an improved traffic sign which is constructed so that it can be placed between car tracks

15 and which is provided with traffic-directing panels or faces situated a few feet from the ground and also with other traffic-directing panels or faces situated high enough above the street level so as to be read over the tops

20 of street cars or other vehicles.

A further object is to provide a novel traffic sign which is constructed so that it takes up a relatively small space transversely of the street, but which nevertheless has the traffic directions exhibited in such a way that they can be readily read.

A further object of the invention is to construct the traffic-directing panels which have thereon the directions regulating traffic so

30 that said panels can be changed to give different directions, such, for instance, as "Stop," "Go," "Go to the right," etc.

A further object is to provide an improved traffic sign which is so constructed

35 that when the panels are set to give some general direction, such, for instance, as "Go to the right," they may be locked in this position, thus making it possible to leave the device at intersecting streets as a "silent

40 policeman."

Other objects of the invention are to provide an improved traffic sign of this type, all as will be more fully hereinafter set forth.

45 In order to give an understanding of my invention, I have illustrated in the drawings, a selected embodiment thereof which will now be described, after which the novel features will be pointed out in the appended claims.

In the drawings, Figure 1 is a view showing my improved traffic signal;

Fig. 2 is a vertical central section through the upper part of the signal;

55 Fig. 3 is a section on the line 3—3, Fig. 8;

Fig. 4 shows the face of one of the panels 8;

Fig. 5 is a top plan view;

Fig. 6 is a section on the line 6—6, Figs.

60

1 and 2;

Fig. 7 shows the reverse side of the panels

25 or 26;

Fig. 8 is a section on the line 8—8, Fig. 1.

1 indicates the base on which my improved sign is supported. This base is provided with a head 2 having radially-extending panel-receiving grooves 3 in which the ends of vertically-arranged radially-extending traffic-directing panels 4 are received. These panels are clamped to the head 2 by

70

means of an upper head 5 which also has in its under face grooves to receive the ends of the panels 4. The two heads 5 and 2 are clamped onto the ends of the panels 4 so as to firmly hold the panels in position, and

75

for this purpose I have provided a connecting member 6 which is situated axially of the heads and which is screw-threaded into the head 2, said connecting member extending through an opening in the head 5. A

80

clamping nut 7 is screw-threaded to the upper end of the connecting member 6 and thus serves to firmly clamp the heads against the panels. The panels 4 are each relatively

85

narrow, that is, they each have a relatively long vertical dimension and a relatively short transverse dimension and they are so arranged that their inner edges are spaced from the axial line, thus leaving a sufficient space between said inner edges to receive the

90

connecting member 6. This construction provides a traffic-directing panel 4 on which any desired legend or traffic direction can be printed in letters large enough to be readily read at a distance, especially if the letters of the words are placed one above the other, as shown in the drawings. A traffic sign having this construction takes up very little room transversely of the street

95

so that it is admirably adapted for use on relatively narrow streets where it is necessary to obstruct the traffic as little as possible.

The panels 4 which are fixed in position will preferably have printed thereon some general direction which is applicable to all conditions of traffic, such, for instance, as "Go to the right".

Situated above the panels 4 are other movably-mounted traffic-directing panels which

105

110

have different directions printed thereon. Some of these other panels may bear the word "Stop"; others may bear the word "Go", and these other panels are movably mounted so that the different directions thereon can be brought into position. In the illustrated embodiment of the invention there are two sets of these movable panels. One set is situated at a distance from the ground equal to about the height of an ordinary person, and another set is situated much higher and arranged to be read over the tops of passing vehicles. There are four of the latter traffic-directing panels and they are indicated at 8 and 9. The two panels 8 each bear a legend or word, such as "Stop", directing traffic movement to cease, while the other panels 9 bear a legend or word such as "Go" directing traffic movement to proceed. These panels are arranged so as to face in four different directions, as usual in traffic signs, the two panels 8 being situated opposite each other and facing in opposite directions, the panels 9 being also situated opposite each other and facing in opposite directions. These panels 8 and 9 are mounted on a supporting member 10 which is of sufficient length so that the panels 8 and 9 are situated above the passing vehicles. The supporting member 10 may be sustained in various ways. I have herein shown the lower end thereof as setting into the tubular connecting member 6. Said member 10 has a collar 11 thereon which engages the nut 7 and sustains the supporting member in its proper position. The support 10 is capable of turning movement through 90° so that the positions of the panels 8 and 9 can be interchanged. This is herein provided for by a handle 12 which is secured to the lower end of the supporting standard 10 and extends through a slot 60 in the tube 6. The handle is shown as pivoted to a lug 61 extending from the member 10 so that said handle will normally hang in a vertical position shown in Fig. 3, but by turning the handle into a horizontal position, as shown by full lines, Fig. 3, and then swinging the handle horizontally, the standard 10 and the panels will be given a quarter revolution, thus reversing the commands given in each direction by the signal.

If it is desirable or necessary to leave the signal unattended, then it is necessary to change the panels 8 and 9 so that they will not give the directions to "Stop" and "Go". To provide for this, I have pivotally mounted the panels on the support 10 to turn about horizontal axes so that said panels may be swung into horizontal planes, thus carrying the "Stop" and "Go" indications out of sight. The support 10 is shown as provided with arms 13 to which the panels 8 and 9 are pivoted at 14. Each panel has

pivots connected to the upper edge thereof of a strut member 15 which in turn is pivoted to a runner 150 slidably mounted on the supporting standard 10. The standard 10 is preferably made tubular and situated therewithin is an actuating member 17 which is connected to the runner 150 through a slot 18 formed in the tube 10. The lower end of this actuator is provided with a laterally-extending arm 19 which projects through a slot 20 formed in the tubular member 10, said slot and arm being situated at a distance from the ground at which it can be conveniently operated. By moving the arm 19 downwardly in the slot 20, the runner 150 will be drawn down on the tubular member 10 and the panels 8 and 9 will be turned about their axes into horizontal planes. When in this position, the words "Stop" and "Go" thereon will be on the upper side 85 of the panels and cannot, therefore, be seen, so that said panels become inoperative so far as giving directions is concerned:

I have provided herein means for locking the panels 8 and 9 either in their operative or in their inoperative position, this being done by locking the actuator 17 either in its elevated or lowered position. The arm 19 is shown as having a U-shaped locking member 21 pivoted thereto, and this locking member is adapted to be swung over a keeper 22 when the actuator 17 is raised, or over another keeper 23 when the actuator 17 is lowered. The locking member 21 may be locked to either of the keepers 22 or 23 by means of a padlock 24 or any other suitable device.

In addition to the panels 8 and 9, I have illustrated herein other traffic-directing panels 25 and 26, there being two oppositely-disposed panels 25, each having the word "Stop" thereon, and two oppositely-disposed panels 26, each having the word "Go" thereon. These panels 25 and 26 are situated just above the fixed panels 4 and are carried by the support 10 so as to turn therewith. When, therefore, the upper panels 8 and 9 are in their operative position, there will be two sets of panels displayed, one at about the height of an ordinary person and the other at a sufficient altitude to be visible over the tops of vehicles. The panels 25 and 26 are preferably reversible panels, said panels having on one side the words "Stop" and "Go," as above described, and on the other side, some general directions applicable to all traffic conditions, such, for instance, as "Go to the right." These panels 25 and 26 are also preferably pivotally sustained so that they can be reversed, thus making it possible to cause them to exhibit either the "Stop" and "Go" directions or the "Go to the right" directions. While any suitable way of supporting these panels 25 and 26 might be adopted, I have herein shown each panel as

provided with two trunnions 27 and 28 which are journaled in bearings 29 formed on brackets 30 secured to the standard 10. These trunnions extend vertically so that 5 the panels 25 and 26 are adapted to turn about vertical axes. The lower trunnion 27 of each panel has a pinion 31 rigid therewith and the pinions 31 all mesh with an actuating gear 32 mounted to turn on the 10 standard 10 and provided with a handle 33 by which it may be actuated. The panels 25 and 26 are of such a size that when they are in their operative position, the edge of one panel stands closely adjacent to or meets 15 the edge of the adjacent panel, as seen in Fig. 5. The gearing 31, 32 is such that a partial turn of the driving gear 32 will give the gears 31 a half rotation, thus reversing the position of the panels.

20 So long as a traffic officer is in attendance at the sign for operating it, the panels 25 and 26 may be positioned so as to exhibit the "Stop" and "Go" legends. If, however, it is desired to leave the traffic signal unattended, then it is important that the legends thereon should be of a general character, such as "Go to the right." When this condition is desired, the operator will actuate 25 the gear 32 so as to reverse the position of the panels 25 and 26 and he will also operate the actuator 17 to swing the upper panels 8 and 9 into their horizontal positions, as above described. The signal when thus adjusted gives general directions and may be 30 left unattended at intersecting streets or any other place where the services of a "silent policeman" will be advantageous.

While I have illustrated herein a selected embodiment of my invention, I do not wish 40 to be limited to the constructional features shown.

I claim:

1. In a traffic sign, the combination with a vertical supporting standard capable of 45 turning about a vertical axis, of a plurality of traffic-directing panels, each pivotally mounted thereon to turn about a horizontal axis, means to turn the standard about its axis to cause each panel to face in either one 50 of two directions, and means operative in any position of the standard to turn said panels so as to present their traffic-directing faces either in a vertical plane where they are exposed to view, or in a horizontal 55 plane.

2. In a traffic sign, the combination with a supporting standard, of a plurality of traffic-directing panels, each pivotally mounted thereon to turn about a horizontal 60 axis, said panels being arranged to face in different directions, means to turn the standard about a vertical axis thereby to change the direction in which each panel faces, and means to turn the panels about 65 their horizontal axes to bring their legend-

bearing faces into or out of a position in which they can be seen.

3. In a traffic sign, the combination with a supporting standard having a plurality of arms at its upper end, of a plurality of 70 traffic-directing panels each journaled at its ends in two of the arms to turn about a horizontal axis, and means to turn said panels so as to present their traffic-directing faces either in a vertical plane where they 75 are exposed to view or in a horizontal plane.

4. In a traffic sign, the combination with a supporting standard, of a plurality of traffic-directing panels surrounding the standard and pivotally mounted thereon to 80 turn about vertical axes, and means to turn said panels simultaneously to reverse the position of each panel.

5. In a traffic sign, the combination with a supporting standard, of two pairs of oppositely-disposed parallel traffic-directing panels, the panels of one pair being situated at right angles to those of the other pair, means for pivotally mounting each panel on the standard to turn about a vertical axis, 90 and means common to all the panels by which the position of all of them can be reversed simultaneously.

6. In a traffic sign, the combination with a supporting standard, of two pairs of 95 traffic-directing panels, the panels of each pair being parallel to each other and those of one pair being situated at right angles to those of the other pair, each panel having a traffic-directing legend on each side thereof, 100 means supporting each panel on the standard for turning movement about a vertical axis, and means common to all the panels by which the position of all of them can be reversed simultaneously. 105

7. In a traffic sign, the combination with a base provided at its upper edge with a head provided with panel-receiving grooves, of a plurality of traffic-directing panels occupying said grooves, said panels having a 110 relatively long vertical dimension and a relatively-short transverse dimension, an upper head engaging the upper ends of the panels, a tubular connecting rod for drawing the two heads toward each other and clamping 115 the panels securely between them, a supporting standard, set into the tubular connecting rod, traffic-directing panels carried by the standard, and means for turning the standard in said connecting rod thus to present 120 the panels thereon in different directions.

8. In a traffic sign, the combination with a base provided at its upper edge with a head having panel-receiving grooves, of a plurality of traffic-directing panels occupying said grooves, each panel having a relatively long vertical dimension and a relatively short transverse dimension, an upper head engaging the upper ends of said panels, 125 a connecting member for drawing the two 130

heads toward each other and clamping the panels securely between them, a supporting standard, and other traffic-directing panels pivotally mounted thereon above the first-
5 named traffic-directing panels.

9. In a traffic sign, the combination with a base provided at its upper edge with a head having a plurality of radially-extending panel-receiving grooves, of a plurality of traffic-directing panels having their lower ends occupying said grooves, each panel having a relatively long vertical dimension and a relatively short transverse dimension and said panels being situated so that their inner
10 edges are spaced from the axial line of the base, an upper head engaging the upper ends of said panels, and a connecting member for drawing the two heads toward each other and clamping the panels securely between
15 them, said connecting member being situated axially of the heads and in the space between the inner edges of the panels.

10. In a traffic sign, the combination with a base provided at its upper edge with a head having a plurality of radially-extending panel-receiving grooves, of a connecting member rising from said head and situated axially thereof, a plurality of radially-extending traffic-directing panels situated
20 outside of said connecting member and hav-
25

ing their lower ends occupying the grooves of said head, each panel having a relatively long vertical dimension and a relatively short transverse dimension, an upper head engaging the upper ends of said panels, and
35 means coöperating with the connecting member for clamping the upper head against the panels.

11. In a traffic sign, the combination with a base provided at its upper edge with a head having panel-receiving grooves, of a plurality of traffic-directing panels occupying said grooves, each panel having a relatively long vertical dimension and a relatively short transverse dimension, an upper head engaging the upper ends of said panels, a connecting member for drawing the two heads toward each other and clamping the panel securely between them, a supporting standard, other traffic-directing panels pivotally mounted thereon above the first-named traffic-directing panels, said supporting standard being capable of turning movement to cause each traffic-directing panel thereon to face in either one of two directions, and means to turn the pivotally-mounted panels about their axes.
